CLAIM

The ornamental design for a DNA sequencing cabinet, as shown.

DESCRIPTION

FIG. 1 is a perspective view of a DNA sequencing cabinet showing the front, top and left side of my new design with the cabinet and keyboard closed;

FIG. 2 is a front elevational view of the embodiment of FIG. 1;

FIG. 3 is a left side elevational view of the embodiment of FIG. 1;

FIG. 4 is a right side elevational view of the embodiment of FIG. 1;

FIG. 5 is a top plan of the embodiment of FIG. 1;

FIG. 6 is a bottom plan view of the embodiment of FIG. 1;

FIG. 7 is a rear elevational view of the embodiment of FIG. 1;

FIG. 8 is a perspective view of a DNA sequencing cabinet showing the front and left side of my new design with the cabinet open and the keyboard closed; and,

FIG. 9 is a perspective view of a DNA sequencing cabinet showing the front and right side of my new design with the cabinet closed and the keyboard open.
